UNITED STATES PATENT OFFICE.

JOHN A. HARRIS, OF LOS ANGELES, CALIFORNIA.

FOLDING IRONING-BOARD.

1,121,092.

Specification of Letters Patent. Patented Dec. 15, 1914.

Application filed April 18, 1914. Serial No. 833,755.

To all whom it may concern:

Be it known that I, JOHN A. HARRIS, a citizen of the United States, residing at 1849 West Jefferson street, Los Angeles, county 5 of Los Angeles, State of California, have invented a new and useful Folding Ironing-Board, of which the following is a specification.

My object is to make a folding ironing 10 board which may be rigidly mounted upon the wall and which will fold up against the wall when out of use and my invention consists of the novel features herein shown, described and claimed.

Figure 1 is a side elevation of a folding ironing board embodying the principles of my invention fastened to a wall and in position for use. Fig. 2 is a front view with the door open as indicated by the arrow 2 in Fig. 1. Fig. 3 is a fragmentary, sectional detail on the line 3-3 of Fig. 4. Fig. 4 is a fragmentary, sectional detail on the line 4-4 of Fig. 3. Fig. 5 is a fragmentary, sectional detail on the line 5-5 of Fig. 4.

The casing is attached to the wall 2 by brackets 3, said casing being rectangular in front elevation and high enough to receive the ironing board 4. The casing 1 comprises the sides 5 and 6 and the ends 7 and 8 rigidly secured together like a box. A piece of sheet metal forms the back 2 of the casing and the front is closed by a swinging door 9. Bearing blocks 10 and 11 are inserted and rigidly mounted in the lower corners of the casing 1 and the bar 12 has pintles 13 upon its ends extending loosely into the bearing blocks 10 and 11. The brace 14 is rigidly secured to the center of the bar 12 and is of considerable length. Bearing 20 blocks 15 are secured to the lower face of the front end of the board 4 and pintles 16 extend from the upper end of the brace 14 into these bearing blocks. Guide blocks 17 and 18 are fastened against the inner faces 25 of the side pieces 5 and 6 so as to form the guide ways 19 and pintles 20 extend from the lower corners of the board 4 into these guide ways. Notches 21 are formed near the upper end of the guide block 17 to receive the pintles 20 when the board proper 30 is in its horizontal position. A stop plate 22 is secured across each guide way 19 and

to the inner faces of the guide bars 17 and 18 above the notches 21 to hold the pintles 20 from going above the notches 21. 55

Wedges 23 are mounted in the upper ends of the guide ways 19, there being pins 24 operating through L shaped slots 25 so that the wedges may slide up and down, the lower ends of said wedges fitting behind the 60 pintles 20 to hold said pintles in the notches 21.

When the ironing board is in its folded position as in Fig. 2, the pintles 20 are in the lower ends of the guide ways 19, the brace 14 is folded up against the lower face of the board 4 and the board 4 is between the side pieces 5 and 6. When it is desired to use the ironing board the door 9 is opened and the board 4 pulled to a horizontal position, the pintles 20 sliding upwardly in the guide ways 19 to the notches 21 and then the wedges 23 are pressed downwardly and the board is held rigidly in its horizontal position. 75

The ironing board as shown and described is to be produced as an article of manufacture ready to be installed by attaching the brackets 3 to the wall, and this portable, self contained feature distinguishes my invention to that extent from the constructions of other disappearing articles which are built into the walls. 80

The details of construction may be varied in many ways without departing from the 85 spirit of my invention as set up in the following claim:

I claim:

In a folding ironing board construction a casing comprising a back, a bottom, two 90 side pieces and a top; a door forming the front of the casing; bearing blocks mounted in the lower corners of the casing; a bar mounted between the bearing blocks; pintles extending from the bar into the bearing 95 blocks; a brace rigidly secured to the center of the bar; an ironing board proper; second bearing blocks secured to the lower face of the front end of the ironing board proper; pintles extending from the upper end of the 100 brace into the second bearing blocks; guide blocks facing against the inner faces of the sides of the casing so as to form vertical guide ways; pintles extending from the

1,121,092

lower corners of the ironing board proper into these guide ways there being notches near the upper ends of the guide blocks and near the upper ends of the guide ways to receive said pintles; stop plates secured across each guide way above the notches and wedges slidingly mounted in the upper ends of the guide ways to hold the pintles in said notches.

JOHN A. HARRIS.
